US0D1108032S

(12) **United States Design Patent** (10) **Patent No.:** **US D1,108,032 S**
(45) **Date of Patent:** **** Dec. 30, 2025**

(54) **BIRD SWING**

(71) Applicant: **Pop's Birding Co., LLC**, Idaho Falls, ID (US)

(72) Inventors: **Bethany Sloan**, Iona, ID (US); **Peter Stankovich**, Iona, ID (US)

(73) Assignee: **Pop's Birding Co., LLC**, Idaho Falls, ID (US)

(**) Term: **15 Years**

(21) Appl. No.: **29/978,147**

(22) Filed: **Dec. 11, 2024**
